LANCELOT JOHNSON, OF ISLINGTON, LONDON, ENGLAND.

MAGNETO STARTING MECHANISM.

1,294,277.

Specification of Letters Patent. Patented Feb. 11, 1919.

Application filed November 12, 1918. Serial No. 262,213.

To all whom it may concern:

Be it known that I, LANCELOT JOHNSON, a subject of the King of England, residing in Islington, London, in England, have invented certain new and useful Improvements in Magneto Starting Mechanism, of which the following is a specification.

This invention relates to starting mechanism for magnetos of internal-combustion engines of the type wherein the engine-shaft and magneto-spindle are operatively connected together by a member on the engine-shaft which when the engine-shaft is turned by hand is moved angularly relatively to one on the magneto-spindle, one of these members is mounted to slide endwise under spring-control, the two members are inter-engaged by a cam-surface on one and a co-operating part thereon on the other in such manner that relative angular movement thrusts the endwise-movable member back against its spring, and a trip-piece is provided which holds back one of the members, so that the said relative angular movement can take place, and then is tripped so that the sliding member can advance under the action of its spring, and impart angular movement to the magneto-spindle in the direction of the engine-drive.

Heretofore it has been necessary with devices of this kind to re-set the tripping-mechanism at each operation or to hold it in one position by a separately operated part which afterward had to be thrown out of action by the gear. A primary object of the present invention is to eliminate any separately-operated part, so that the whole becomes automatic, and to simplify the mechanism.

To this end, one form of the improved starting mechanism comprises the slideable member, its co-operating member, and a stationary stop, in combination with a lever which is pivoted to one of these members to lock it against angular movement relative to the stop and is so placed as to be automatically tripped by the other member when the engine-shaft member has been given a predetermined angular movement relatively to the magneto-spindle member.

Another object is to provide that the lever used as the trip-piece shall be centrifugally controlled, so that after being tripped it will keep out of its locking position.

To these and other ends, the invention consists in the construction, arrangement and combination of parts described hereinafter and pointed out in the claims.

One embodiment of the invention is illustrated by way of example in the accompanying drawings, wherein:

Figure 1 is a plan of the starting mechanism with the parts in the tripping position;

Fig. 2 is an approximately horizontal section through the mechanism with the parts shown just beyond the tripping position, the actual line of section being that indicated by the line 2-2 in Fig. 3;

Fig. 3 is a transverse section through the mechanism taken on the bent line 3-3 in Fig. 2, and

Fig. 4 is an end elevation of the mechanism viewed from the engine-shaft end and with the parts in the position prior to tripping.

Like letters indicate like parts throughout the drawings.

The magneto-spindle A has fast upon it a cup-shaped member A¹, the open side of which is toward the engine-shaft B. The edge of the cup-shaped member is shaped to provide a cam face A² with a pocket A³ therein. Fast on the engine-shaft B is an annular member B¹ which projects into the cup-shaped member A¹ and has sliding upon it a sleeve or ring B² which also enters the cup-shaped member A¹. The ring B² is provided with splines B^{2*} which slide in keyways B^{1*} in the member B¹. A spring C surrounds the member B¹ and bears at one end against the ring B² and at the other end against a flange on the member B¹. This spring, therefore, always tends to thrust the ring B² into the member A¹; projecting laterally from the ring are pins carrying rollers B³ which bear against the cam face A² of the member A¹.

Pivoted to the exterior of the member A¹ are levers D. These are pivoted to ears D¹ about axes which lie at right-angles to the axis of rotation of the engine-shaft and are so disposed that the ends of the levers can move toward and away from the engine-shaft. The levers have short arms projecting toward the magneto which lie in the path of a stationary stop E when these arms are swung outward, and they have longer arms on the engine side which ends

carry rollers D². The rollers coöperate with cams B⁴ carried by the flange on the member B¹.

The stop E is carried by a post E¹ which 5 is a fixture relatively to the magneto casing, and at the front of the stop is a buffer spring E². The post E¹ also carries a guard E³ which is still farther in advance of the stop, so that when the parts are revolving it meets 10 the levers before these reach the stop, and the guard is set so far in toward the levers that the short arms of the same which engage the stop E are pushed into the non-engaging position relatively to the stop if 15 they should already be cut in the engaging position.

Two pins F are secured to the flange on the part B¹ and project into the pockets A³ of the member A¹. The end of each pin F 20 is shaped to form a flat spring and when the rollers B³ are in the pockets these flat ends bear against the approximately vertical faces A^{2*} of the pockets A³.

The operation of this device is as follows: 25 When the engine-shaft B is turned by hand the member B¹ and consequently the ring B² thereon is carried around with it. When thus started the rollers B³ carried by the ring B² lie in the pockets A³ of the 30 member A¹ and as the cam-face A² is steep, the rollers carry the member A¹ around with them. The levers D are thus carried around with the member A¹ and as either lever comes to the top, the long arm will drop 35 down toward the engine-shaft and the short arm will be raised ready to engage the stop E. In passing under the guard E³, the raised arm is momentarily depressed for reasons hereinafter described, but the 40 arm again rises before reaching the stop, and is thus stopped by the latter, the blow being eased by the buffer spring E². This arrests further angular movement of the member A¹ so that relative angular movement 45 now takes place between this member and the engine-shaft member B². Continued movement of the engine-shaft therefore causes the rollers B³ to ride up the cam-faces A² on the member A¹, whereby the 50 ring B² is thrust back and the spring C is compressed. When the rollers reach approximately the tops of the cam-faces A² the cams B⁴ on the flange of the member B¹ arrive at the engine-shaft ends of the 55 levers D, so that whichever lever is in contact with the stop E it is disengaged therefrom by the cam thrusting the long arm outward, and the member A thus being released is suddenly advanced by the rollers 60 B³ running down the cam-faces A² into the pockets A³.

The shock of the parts is absorbed by the springs F which arrest the angular movement of the member A by engaging 65 the faces A^{2*} and thus the endwise move-

ment of the ring B² is also brought to rest with little shock, as the rollers do not reach the bottoms of the pockets A³ but are prevented from doing so by the resilient action of the springs F; that is to say, the springs 70 F prevent the part A¹ from moving around sufficiently far relatively to the ring B² to allow the rollers B³ to reach the bottoms of the pockets A³, and thus the relative angular movement of the parts and the 75 relative endwise movement of the parts are both resiliently arrested.

If the engine has now started, the speed of rotation causes the long arms of the levers D to fly out under centrifugal action, 80 so that the short arms are now kept in and thus do not come into contact with the stop E, and driving is effected by the engagement of the rollers B³ with the steep portions of the cam faces A², the rollers 85 being kept in the pockets by the thrust of the spring C.

The object of the guard E³ is to prevent the levers from coming against the stop E when the engine is running slowly. It 90 insures that if the engaging arm of the lever should be in position for engaging the stop when passing vertically over the axis of rotation, this shall be thrust in before reaching the stop and thus, if the engine 95 is running then at a slow speed, it will not have time to rise again before it has passed under the stop, whereas when turning the engine around by the crank-handle, which is a much slower action, the interval of time 100 between leaving the guard E³ and reaching the stop E is such that the lever can again reach the engaging position. It will be noted also that the stop is not placed vertically above the axis of rotation of the engine-shaft, but over to one side of the 105 same, so that the action of gravity shall not be so severe as would be the case if the stop were vertically above the said axis of rotation; this also operates toward the same 110 end, namely guarding against the levers striking the stop when the engine is running slowly.

What I claim as my invention and desire to secure by Letters Patent is:— 115

1. In magneto starting-mechanism of the type described, the combination with an engine-shaft, a magneto-shaft, a member fixed on one of said shafts, a spring-controlled member mounted to slide axially and to rotate relatively to the other shaft, one of said members normally coacting with a cam-face on the other and adapted to impart relative angular movement thereto and to slide the said spring-controlled member axially against the action of its spring, of a fixed stop, and a lever which is pivoted on one of said members, is adapted to coact with and to be temporarily arrested by said stop to lock the member 120 125 130

carrying the lever against angular movement relatively to the stop, and is adapted to be automatically tripped by the other of said members when the engine-shaft has 5 moved a predetermined angular distance relatively to the magneto-shaft.

2. In magneto starting-mechanism of the type described, the combination with an engine-shaft, a magneto-shaft, a member fixed 10 on one of said shafts, a spring-controlled member mounted to slide axially on and to rotate about the other shaft, one of said members normally coacting with a cam-face on the other and adapted to impart relative 15 angular movement thereto and to slide the said spring-controlled member against the action of its spring, of a fixed stop, and a lever which is pivoted on the magneto-shaft member, is adapted to coact with and to be 20 temporarily arrested by said stop to lock the magneto-shaft member against angular movement relatively to the stop, and is adapted to be automatically tripped by the engine-shaft member when the same has 25 moved a predetermined angular distance relatively to the magneto-shaft member.

3. In magneto starting-mechanism of the type described, the combination with an engine-shaft, a magneto-spindle in alinement 30 therewith, a member fixed on the magneto-spindle, a spring-controlled member mounted to slide axially and to rotate relatively to the engine-shaft, one of said members normally coacting with a cam-face on the 35 other and adapted to impart relative angular movement thereto and to slide the said spring-controlled member axially against its spring and thereby load the latter, of a fixed stop, a cam fast on the engine-shaft, and a lever which is pivoted on one of said members and is adapted to coact with said cam and be automatically tripped thereby when the engine-shaft member has moved a predetermined angular distance relatively to 40 the magneto-spindle member.

4. In magneto-starting-mechanism of the type described, the combination with an engine-shaft, a magneto-spindle in alinement therewith, a member fixed on the magneto-spindle, a spring-controlled member mounted to slide axially and to rotate relatively to the engine-shaft, one of said members normally coacting with a cam-face on the other and being adapted to impart relative 55 angular movement thereto and to slide the said spring-controlled member axially relatively to its spring, of a fixed stop, a cam fast on the engine-shaft, and a double-ended lever having arms of unequal length which 60 is fulcrumed on the magneto-spindle member and has its shorter arm adapted to coact with and to be temporarily arrested by said stop to lock the magneto-spindle member against angular movement relatively to the 65 stop, the longer arm of the lever being

adapted to coact with said cam to trip the lever from said stop when the engine-shaft member has moved a predetermined angular distance relatively to the magneto-spindle member.

70

5. In magneto starting-mechanism, the combination of an engine-shaft, a magneto-spindle in alinement therewith, a cup-shaped member having a cam-shaped edge fixed on the magneto-spindle, an annular member 75 having a cam on the periphery thereof fixed on the engine-shaft, a sleeve slidably splined on the annular member and entering into the cup-shaped member, said sleeve having radial projections arranged to coact with the 80 cam-shaped edge of the latter, a spring arranged to tend to move said annular member axially relatively to said sleeve, a fixed stop, and a lever which is pivoted on the cup-shaped member, is adapted to coact with 85 and to be temporarily arrested by said stop to lock the cup-shaped member against angular movement relatively to the stop, and is adapted to coact with said cam to be automatically tripped thereby to release the cup-shaped member when the said annular member 90 has moved a predetermined angular distance relatively to the latter.

6. In magneto starting-mechanism, the combination with an engine-shaft, a magneto-shaft, a member fixed on one of said shafts, a spring-controlled member mounted to slide axially and to rotate relatively to the other shaft, one of said members normally coacting with a cam-face on the other 100 and adapted to impart relative angular movement thereto and to slide the said spring-controlled member axially relatively to its spring, of a fixed stop, a lever which is pivoted on one of said members, is adapted to coact with and to be temporarily arrested by said stop to lock the member carrying the same against angular movement relatively to the stop, and is adapted to be automatically tripped by the other of said members 105 110 when the engine-shaft member has moved a predetermined angular distance relatively to the magneto-shaft member, and a flat spring which is carried by one of said members and projects therefrom in a line approximately parallel with the line of axial movement thereof and is adapted to engage a part of the other of said members to limit the relative angular movement of the said members after the lever has been tripped.

115

7. In magneto starting-mechanism, the combination of an engine-shaft, a magneto-spindle in alinement therewith, a cup-shaped member having a cam-shaped edge fixed on the magneto-spindle, an annular member having a cam on the periphery thereof fixed on the engine-shaft, a sleeve slidably splined on the annular member and entering into the cup-shaped member, said sleeve having radial projections arranged to 120 125 130

4

coact with the cam-shaped edge of the latter, a spring arranged to tend to move said annular member axially relatively to said sleeve, a fixed stop, a lever which is pivoted on the cup-shaped member, is adapted to coact with and to be temporarily arrested by said stop to lock the cup-shaped member against angular movement relatively to the stop, and is adapted to coact with said cam 5 to be automatically tripped thereby to release the cup-shaped member when the said annular member has moved a predetermined angular distance relatively to the latter, and a flat spring carried by said annular member 10 and projecting into a recess in the said cam-shaped edge of the cup-shaped member in a direction approximately parallel with the axis of the engine-shaft.

8. In magneto starting-mechanism of the type described, the combination with an engine-shaft, a magneto-spindle in alinement therewith, a member fixed on the magneto-spindle, a spring-controlled member mounted to slide axially and to rotate relatively to the engine-shaft, one of said members normally coacting with the cam-face on the other and adapted to impart relative angular movement thereto and to slide the said spring-controlled member axially 20 relatively to its spring, of a fixed stop, a cam fast on the engine-shaft, a double-ended lever having arms of unequal length which is fulcrumed on the magneto-spindle member and has its shorter arm adapted to coact 25 with and to be temporarily arrested by said stop to lock the magneto-spindle member against relative angular movement relatively to the stop, the longer arm of the lever adapted to coact with said cam to trip the lever from said stop when the engine-shaft 30 member has moved a predetermined distance relatively to the magneto-spindle member, and a guard carried by said stop and adapted to coact with the shorter arm of the lever 35 when the same is at a small angular distance from the stop for forcing the same into its non-engaging position with the stop.

9. In magneto starting-mechanism of the type described, the combination with an engine-shaft, a magneto-shaft, a member fixed on one of said shafts, a spring-pressed member mounted to slide axially on and to rotate about the other shaft, one of said members normally coacting with a cam fast on 40 the other and being adapted to impart relative angular movement thereto and to slide the said spring-pressed member axially against its spring and thereby compress the latter, of a fixed stop, and a lever having arms of unequal length which is pivoted on 45 one of said members, the shorter arm of the lever being normally adapted to coact with and to be temporarily arrested by said stop to lock the member carrying the same against angular movement relatively to the stop, the said lever being adapted to be automatically tripped by the other of said members when the engine-shaft member has moved a predetermined angular distance relatively to the magneto-shaft member, and being located approximately parallel to the axis of rotation of the engine-shaft and pivoted to rock about an axis at right-angles thereto and so disposed that the longer arm of the lever is adapted to swing away from the shaft under action of centrifugal force to place the shorter arm of the lever out of reach of said stop.

10. In magneto starting-mechanism of the type described, the combination of an engine-shaft, a magneto-spindle in alinement therewith, a cup-shaped member having a cam-shaped edge fixed on the magneto-spindle, a flanged annular member having a cam on the periphery thereof fixed on the engine-shaft, a ring slidably splined on the annular member and having radial projections normally coacting with the said cam-shaped edge, a compression spring arranged between the flange of the annular member and said ring, a flat spring carried by said flange and projecting into a recess in the said cam-shaped edge, a fixed stop, a guard carried by the stop, and a double-ended lever, having a longer and a shorter arm, which is fulcrumed on the cup-shaped member and has its shorter arm adapted to coact with said guard and be forced into one extreme non-engaging position and thereafter to be temporarily arrested by said stop to lock the cup-shaped member against angular movement relatively to the stop, the said longer arm adapted to coact with said cam to trip the lever from said stop when the annular member has moved a predetermined distance relatively to the cup-shaped member.

In testimony whereof I affix my signature.

LANCELOT JOHNSON.
